CLOTHES DRIER

Charles L. Richardson, Belmont, Mass.

Application March 24, 1948, Serial No. 16,703

5 Claims. (Cl. 34—239)

1

This invention relates to a portable clothes drier and its principal objects are to provide an efficient drier for home use, which may be hung on a wall, supported on a table or bench, or otherwise conveniently positioned during use, and which is designed to dry out clothing and the like articles in a relatively short period; and to provide a drier which is of relatively light weight, but of strong and durable construction, which is compact and capable of being easily handled, and which may be manufactured and sold at a relatively low cost.

Further objects will be apparent from a consideration of the following description and the accompanying drawings, wherein:

Fig. 1 is a side elevation, with parts broken away and shown in section of a clothes drier constructed in accordance with the present invention;

Fig. 2 is a top plan view, with parts broken away, of the drier shown in Fig. 1;

Fig. 3 is a section on the line 3—3 of Fig. 2; and

Fig. 4 is an elevation illustrating the manner in which the drier may be hung on a wall.

The embodiment herein shown for the purpose of illustration comprises an elongate crib-like body 1, preferably of a reflecting metal such as aluminum, stainless steel, tin plate or the like, and which is of generally parabolic or arcuate cross section. A channel-like support 2 is soldered, welded or otherwise secured to the base or bottom wall portion of the body so that the drier may be supported in a horizontal position, as shown in Fig. 1, or in a vertical position against a wall W, as shown in Fig. 4, in which case the upper end of the channel 2 may be provided with an opening 3 (Fig. 1) to receive a wall hook or the like.

The lower end of the body is somewhat shallower than the upper end or head, as indicated in Figs. 1 and 4, and is provided with an end plate or closure 4 which extends outwardly beyond the side portions of the body 1 to provide a stand or foot which alone is capable of supporting the drier in upright position. If desired, the inner part of the plate 4 may be provided with perforations 5 (Fig. 1) to enhance circulation of air as herein-after described. The head end is also provided with a closure plate 6 which extends outwardly beyond the side wall portions of the body and is inclined toward the opposite end to provide a deflector 8.

A partition 10 (Figs. 1 and 2) extends at an angle of approximately 45° from the bottom wall

2

portion to the outer end portion of the plate 6 and not only provides a baffle, but also defines an enclosed chamber 11 (Fig. 1). A plurality of electrical heating elements 12 are disposed along the bottom wall portion and are maintained in properly spaced relation to each other by longitudinally and transversely extending spacers 14 secured in any suitable manner to a metallic reflector shield 15, the body portion of which is spaced from the adjacent bottom wall portion of the body 1, as shown in Fig. 3, to minimize heat conduction. A relatively coarse screen 16 of convex contour extends above the heating elements 12 from one end thereof to the other and divides 15 the interior of the body 1 into an inner flow channel 17 and an outer flow channel 18, as indicated in Figs. 1 and 3.

A small electric motor 20 is mounted on a bracket 21 within the chamber 11 so that its shaft 22 extends at approximately right angles through an opening in the partition 10, as shown in Fig. 1. The projecting end of the shaft 22 carries a fan blade 25 and the parts are so constructed and arranged that the fan 25 induces a flow of air 25 through the inner channel about the heating elements 12 toward the fan and against the partition or baffle 10 and deflector 8, and a counterflow of the heated air in the outer channel 18, as indicated by the arrows of Fig. 1. The motor 20 and heating elements 12 are connected in parallel in the electrical circuit so that when the cord 28 is connected to an outlet operation of the motor and heater takes place.

Between the opposite ends 4 and 6 is a pair of spaced clothes racks 30 and 31, both of which are pivotally connected to the side wall portions of the body so that they may be swung from a collapsed position substantially parallel to the longitudinal edges of the body to an arcuate position at right angles thereto, as shown in Figs. 1, 3 and 4, or any intermediate position, as desired. The upper rack 30, as shown in Fig. 3, comprises a plurality of spaced arms and the rack 31 is an arcuate-shaped length of metal, but it 45 is to be understood that any other form of clothes rack may be used which will hold or support articles to be dried along the outer flow channel 18 so that they are not only subjected to radiation from the heating elements 12, but also to the heated countercurrent of air induced by the fan 25.

With the construction and arrangement of parts herein shown air is continuously circulated from the lower end of the body, through the inner channel 17 where it is heated, against the

baffle 10 and deflector 8, and then in a generally countercurrent direction along the outer channel 18 through the clothes or articles supported by the racks 30, 31. Thus, such articles are subjected to direct radiation from the heating elements 12, the warm air currents induced by the fan 10 and a slight amount of conduction through the racks 30, 31. When relatively light fabrics such as diapers, underclothing, etc., are properly supported on the racks, it is but a matter of a few minutes to effect complete drying at moderate indoor humidities, and for heavier articles the time required for drying is but a small fraction of what would otherwise be necessary.

It will be noted that the drier may be conveniently positioned horizontally, vertically or inclined, and that when not in use it may be readily collapsed so that it can be stored away in a closet, cabinet or other accessible place.

While I have shown and described one desirable embodiment of the invention, it is to be understood that this disclosure is for the purpose of illustration and that various changes and modifications may be made without departing from the spirit and scope of the invention as set forth in the appended claims.

I claim:

1. A portable clothes drier comprising an elongate crib-like body having a closed end and a partition extending diagonally from the bottom wall portion to the outer edge of said closed end so as to define an enclosed chamber, heating elements extending along the bottom wall portion of said body between the inner end of said partition and the other end of said body, a screen extending above said heating elements so as to divide the interior of said body into longitudinally extending inner and outer flow channels, a motor within said chamber having its shaft extending through said partition, a fan carried by the projecting end of said shaft, the parts being so constructed and arranged that said fan induces a flow of air through the inner channel about said heating elements toward said fan and against said partition and a counterflow of heated air toward said opposite end, and a rack for supporting articles to be dried so that they are suspended in said outer flow channel where they are subjected both to radiation from said heating elements and the counterflow of heated air.

2. A portable clothes drier comprising an elongate crib-like body of arcuate cross-section having a closed end and a partition extending diagonally from the bottom wall portion to the outer edge of said closed end so as to define an enclosed chamber, electrical heating elements extending along the bottom wall portion of said body between the inner end of said partition and the other end of said body, a screen extending above said heating elements so as to divide the interior of said body into longitudinally extending inner and outer flow channels, a motor within said chamber having its shaft extending through said partition, a fan carried by the projecting end of said shaft, the parts being so constructed and arranged that said fan induces a flow of air through the inner channel about said heating elements toward said fan and against said partition and a counterflow of heated air toward said opposite end, and a rack for supporting articles to be dried so that they are suspended in said outer flow channel where they are subjected both to radiation from said heating elements and the counterflow of heated air.

3. A portable clothes drier comprising an elongate

crib-like body having a closed end and a partition extending diagonally from the bottom wall portion to the outer edge of said closed end so as to define an enclosed chamber, heating elements extending along the bottom wall portion of said body between the inner end of said partition and the other end of said body, a screen extending above said heating elements so as to divide the interior of said body into longitudinally extending inner and outer flow channels, a motor within said chamber having its shaft extending through said partition, a fan carried by the projecting end of said shaft, a deflector adjoining the outer end of said partition and inclined toward said opposite end, the parts being so constructed and arranged that said fan induces a flow of air through the inner channel about said heating elements toward said fan and against said partition and deflector and a counterflow of heated air toward said opposite end, and a rack for supporting articles to be dried so that they are suspended in said outer flow channel where they are subjected both to radiation from said heating elements and the counterflow of heated air.

4. A portable clothes drier comprising an elongate crib-like body having a closed end and a partition extending at an angle of approximately 45° from the bottom wall portion to the outer edge of said closed end so as to define an enclosed chamber, heating elements extending along said bottom wall portion between the inner end of said partition and the outer end of said body, a convex screen extending above said heating elements so as to divide the interior of said body into longitudinally extending inner and outer flow channels, a motor within said chamber having its shaft extending through said partition at approximately right angles thereto, a fan carried by the projecting end of said shaft, the parts being so constructed and arranged that said fan induces a flow of air through the inner channel about said heating elements toward said fan and against said partition and deflector and a counterflow of heated air toward said opposite end, and a rack for supporting articles to be dried so that they are suspended in said outer flow channel where they are subjected both to radiation from said heating elements and the counterflow of heated air.

5. A portable clothes drier comprising an elongate crib-like body having a closed end and a partition extending from the bottom wall at approximately 45° to the outer edge portion of said closed end so as to define an enclosed chamber, electrical heating elements extending along the bottom wall of said body between the inner end of said partition and the outer end of said body, a convex screen extending above said heating elements so as to divide said body into longitudinally extending inner and outer flow channels, a motor within said chamber having its shaft extending through said partition at approximately right angles thereto, a fan carried by the projecting end of said shaft, a deflector adjoining the outer end of said partition and inclined toward said opposite end, the parts being so constructed and arranged that said fan induces a flow of air through the inner channel about said heating elements toward said fan and against said partition and deflector and a counterflow of heated air along the outer channel, and a rack pivotally connected to the side wall portions of said body for supporting clothes to be dried so that they are suspended in said outer flow chan-

nel where they are subjected both to radiation from said heating elements and the counterflow of heated air.
